UNITED STATES PATENT OFFICE

109,228

DESIGN FOR A COMBINED DESK AND CHAIR

Erving B. Morgan, Grand Rapids, Mich., assignor
to American Seating Company, Grand Rapids, Mich., a corporation of New Jersey

Application February 28, 1938, Serial No. 75,462

Term of patent 3½ years

To all whom it may concern:

Be it known that I, Erving B. Morgan, a citizen of the United States, residing at Grand Rapids,
in the county of Kent and State of Michigan,
have invented a new, original, and ornamental Design for a Combined Desk and Chair, of which the following is a specification, reference being had to the accompanying drawing, forming a part thereof, in which:—

The figure is a perspective view of the combined desk and chair showing my new design, the dominating and essential feature or characteristic being the supporting structure for the desk and chair which is shown in full lines.

I claim:

The ornamental design for a combined desk and chair, substantially as shown and described.

ERVING B. MORGAN.
